US00D909506S

(12) **United States Design Patent** (10) Patent No.: **US D909,506 S**
(45) Date of Patent: ** Feb. 2, 2021

(54) **GOLF CLUB HEAD**

(71) Applicant: **PARSONS XTREME GOLF, LLC**,
Scottsdale, AZ (US)

(72) Inventors: **Bradley D. Schweigert**, Cave Creek,
AZ (US); **Michael R. Nicolette**,
Scottsdale, AZ (US)

(73) Assignee: **PARSONS XTREME GOLF, LLC**,
Scottsdale, AZ (US)

(**) Term: **15 Years**

(21) Appl. No.: **29/696,812**

(22) Filed: **Jul. 1, 2019**

Related U.S. Application Data

(63) Continuation-in-part of application No. 29/687,953,
filed on Apr. 17, 2019, now abandoned.

CLAIM

The ornamental design for a golf club head, as shown and described.

DESCRIPTION

FIG. 1 is a top perspective view of a golf club head;

FIG. 2 is a bottom perspective view of the golf club head of FIG. 1;

FIG. 3 is a front elevational view of the golf club head of FIG. 1;

FIG. 4 is a rear elevational view of the golf club head of FIG. 1;

FIG. 5 is a top view of the golf club head of FIG. 1;

FIG. 6 is a bottom view of the golf club head of FIG. 1;

FIG. 7 is a left side view of the golf club head of FIG. 1;

FIG. 8 is a right side view of the golf club head of FIG. 1;

FIG. 9 is a top perspective view of a second embodiment of the golf club head;

FIG. 10 is a bottom perspective view of the golf club head of FIG. 9;
FIG. 11 is a front elevational view of the golf club head of FIG. 9;
FIG. 12 is a rear elevational view of the golf club head of FIG. 9;
FIG. 13 is a top view of the golf club head of FIG. 9;
FIG. 14 is a bottom view of the golf club head of FIG. 9;
FIG. 15 is a left side view of the golf club head of FIG. 9;
FIG. 16 is a right side view of the golf club head of FIG. 9;
FIG. 17 is a top perspective view of a third embodiment of the golf club head;
FIG. 18 is a bottom perspective view of the golf club head of FIG. 17;
FIG. 19 is a front elevational view of the golf club head of FIG. 17;
FIG. 20 is a rear elevational view of the golf club head of FIG. 17;
FIG. 21 is a top view of the golf club head of FIG. 17;
FIG. 22 is a bottom view of the golf club head of FIG. 17;
FIG. 23 is a left side view of the golf club head of FIG. 17;
and,
FIG. 24 is a right side view of the golf club head of FIG. 17.
The broken lines shown on the golf club head forms no part of the claimed design.
